ABSTRACT: A toe cleat for a ski binding includes an anti-early release linkage for providing sufficient holding force to the sole of the skier's boot relative to the toe cleat. Operation of the linkage is initiated by sideward excursion of the rotational part of the ski binding; incremental angular rotation of such rotary part is translated to the toe cleat through the link-

age. In one form, the linkage comprises a series of gears including a stationary spur gear in fixed engagement with the hub of the fixed portion of the ski binding; a pair of axially spaced pinion gears fixed on an upright common shaft rotatably connected to the moving portion of the ski binding; one pinion gear is in contact with the stationary gear, and the other pinion gear is in tangential contact with a sector gear formed at the hub of the toe cleat. Since the toe cleat is meshed through the pinion gears to the stationary spur gear, until the binding undergoes rotation, the toe cleat is solid to the ski runner. As the binding undergoes rotation, however, the common shaft is caused to rotate, causing, in turn, corresponding and proportional rotation of the toe cleat. In another form of the invention, the linkage comprises a fixed yoke positioned about the hub of the fixed portion of the binding and a pair of lever members (bars) pivotally attached at one end, to the yoke, and, the other end, to a support for the toe cleat. Since the pivot points of levers are not coincident with the pivot point of the toe cleat, until the binding undergoes movement due to external forces acting on the binding, say as the skier loses his upright stability and starts to fall, the toe cleat is solid to the ski runner. However, when movement of the rotating part of the binding occurs, the toe cleat, cleat support and the twin lever members, are conveyed, in tandem, therewith which causes the connection points at the toe-cleat support to move along arcuate pass centered at the other connection points of the levers. In either form, the linkage is seen to control the extent of rotation of the toe cleat in a manner concomitant with the rotation of the ski binding but in an opposite angular direction; and affix centerlines of the toe cleat and the skier's boot in coincident alignment until the release angle for the ski binding is achieved.

**SKI BINDING HAVING IMPROVED TOE CLEAT
INCLUDING ANTI-EARLY RELEASE LINKAGE**

BACKGROUND OF THE INVENTION

This invention relates to a ski binding having a stationary base solid to a ski runner and a rotational member mounted by yieldable means to the stationary base, and more particularly, to a toe cleat rotatably mounted to the rotational member of the binding so that, during release, the sideward excursion of the boot relative to the centerline of the ski runner is prevented solely by the yieldable means of the binding and, still more particularly, to a toe cleat having as an additional feature, the capability of yieldably providing nonslip engagement between the toe of the ski boot and the rotational member of the binding.

- i. even though the external reaction forces acting on the toe cleat and boot are sufficient to cause rotation of the rotational member of the binding, as say, when a skier loses his upright stability and starts to fall and
- ii. without the necessity or requirement of notches, grooves, or the like at the engaging surfaces of the boot's sole with respect to the toe cleat.

Ski bindings are designed to release when a preselected threshold level is exceeded by external forces acting on the binding. To allow for release, each binding may include a boot-holding means yieldably attached to a ski runner on a pivot and held against rotation (sidewise excursions) by selectively conditioned yieldable means, such as a movable piston sliding in a bore formed in a body member and responsive to the action of a relatively strong compression spring urging the piston against a conforming camming surface solid to the ski runner.

A skier's boot is normally urged in a forward direction by separate forward urging means, say located near the skier's heel. The reaction force acts through the skier's boot to place the boot in positive hold-contact with the toe cleat attached to the binding forward of the heel urging means.

Toe cleats normally are crescent shaped to match the shape of the boot toe and each is separately attached to the rotatable body member of the binding. As explained in my U.S. Pat. No. 3,029,085, entitled "TOE HOLD FOR SKIS" issued Apr. 10, 1962, pivotally attaching the toe cleat to the body member, facilitates release of the boot from the toe cleat when the release angle of the binding is achieved. Since the direction of rotation of the cleat is opposite to that of the body member, wedging of the boot between the toe cleat and the forward urging means at the skier's heel is eliminated. By eliminating the occurrence of reaction forces due to wedging, the binding set forth in my patent, supra, controls sidewise movement of the body member based solely on the reaction force provided by the yieldable means. Thus, release of the boot when the threshold level of the binding is exceeded, is facilitated.

To assure adequate engaging forces between the toe cleat and the boot, normally the sole of the boot, at the toe, is notched or grooved for engagement with the toe cleat. In that way, the toe cleat and boot can be locked against relative incremental movement as the cleat-boot experiences external reaction forces, such as when the skier starts to fall.

Many of today's skiers are fashion conscious and moreover do not wish to have their expensive ski boots notched, grooved, or in any way altered to accommodate the toe cleat. The notches or grooves at the toe may, in some way, or in some manner, detract from the boot's appearance when not affixed on the ski runner. However, in operation, experience has shown that without a grooved boot-cleat engaging surface, the boot can slip from contact from the toe cleat before the release of the binding is reached. Result: early and unexpected—and, therefore, dangerous—release of the boot from the binding.

OBJECT OF THE INVENTION

It is an object of the present invention to provide anti-early release linkage for the toe cleat of a ski binding so that the toe

cleat and the sole of the ski boot, during rotation, can be maintained in a gripping relationship until the rotating part of the binding reaches its preselected release angle measured with respect to the centerline of the ski runner. In that way, even though the mating surfaces between the ski boot and the toe cleat may be smooth, i.e., nongrooved, early release of the boot relative to the toe cleat can be prevented until the preselected release angle is reached.

SUMMARY OF THE INVENTION

Briefly, the present invention provides a precision anti-early release linkage for the toe cleat of a ski binding, which provides sufficient holding force between the ski boot and the toe cleat during all operations so that there can be a total absence of separate notches, grooves, etc., in the sole of the boot to effect its engagement with the cleat. In accordance with the present invention, the linkage is positioned between the rotational and stationary portions of the ski binding and the toe cleat. Operation of the linkage is initiated by sideward excursion, only or not at all, of the rotating portion of the ski binding, the incremental angular rotation of the binding being translated to the toe cleat on a direct proportional basis but in an opposite angular direction.

In one form of the invention, the linkage comprises a series of gears including a stationary spur gear fitted about the hub of the fixed part of the ski binding made solid to the ski runner; and a pair of axially spaced pinion gears fixedly positioned on a common upright shaft which is rotatably connected to the moving portion of the binding. Preferably, one of the pinion gears is in tangential meshing contact with the teeth of the stationary spur gear while the other pinion gear is in tangential meshing contact with a sector gear formed integrally with the hub of the toe cleat. Since the toe cleat is meshed through the pinion gears to the stationary spur gear, until the binding undergoes rotation, the toe cleat is solid to the ski runner. As the ski binding is forced into rotation, however, the common shaft to the pinion gears is caused to rotate since one pinion gear is in meshing contact with the stationary gear.

The other pinion gear also rotates, causing in turn, rotation of the sector gear and the toe cleat. The extent of rotation of the toe cleat is directly linked to the incremental rotation of the ski binding about its pivot pin. Absent initiating movement of the rotating part of the binding, however, the sole of the boot is solidly retained within the cleat even though the external forces acting on the boot and cleat may be quite large, and even though the sole-cleat engagement surface is without the use of grooves, notches, or the like. Further, after initiating rotation of the rotating member of the binding has occurred, the rotation of the toe cleat is proportional thereto, say, 1:1, the centerlines of the boot and cleat remain substantially coincident until the release angle is achieved.

In another form of the invention, the linkage comprises a fixed yoke positioned about the fixed hub of the binding solid to the ski runner, with twin levers pivotally attached, at one end to the yoke and, at the other end, to a support for the toe cleat. Preferably, the connection points of the levers are at positions in a common plane and, at the toe cleat support, are laterally spaced the same approximate distance as that at the yoke. Since the pivot points at the toe cleat support are not coincident with that of the toe cleat, the toe cleat is held solid to the ski runner until initiating rotation of the rotation part of the binding, occurs. However, after movement of the rotating part of the binding occurs, carrying into rotation the toe cleat and its support, the connection points on the cleat move along arcuate paths which cause rotation of the toe cleat relative to the binding. The extent of rotation is likewise directly proportioned to the incremental amount of angular rotation of the ski binding but is in an opposite angular direction. Centerlines of the cleat and boot remain coincident until the release angle of the binding is achieved.

DESCRIPTION OF THE DRAWINGS

To afford a clear understanding of this invention, and the manner in which it may be carried out in practice, reference is now made to the accompanying drawings in which:

FIG. 1 is a perspective view, partially exploded, illustrating the toe cleat and anti-early release mechanism of the present invention.

FIG. 2 is a perspective view, again partially exploded, illustrating a second embodiment of the toe cleat and anti-early release mechanism of the present invention.

DESCRIPTION OF PREFERRED EMBODIMENTS

Reference is now made to the drawings. FIG. 1 illustrates an embodiment of the present invention depicting ski binding 10 adapted to be disconectably connected to a ski boot (not shown) along centerline C—C of ski runner 11. The ski boot is engaged with central body member 12 of the binding 10 through a toe cleat 13, the boot being urged into contact with the cleat 13 by suitable urging means located at the heel portion of the boot (not shown). Stationary base 14 of the binding is made solid to the ski runner 11 symmetrical with the centerline C—C, as by screws extending through openings 15. The base 14 also includes a central hub 16 which attaches by notches 17 to an upright, stationary, cam member (not shown) within the interior of the body member 12. As explained in detail, in my U.S. Pat. No. 3,430,971, entitled "SKI BINDING," issued Mar. 14, 1969, and incorporated herein by reference, the threshold level (actuation) of the rotating member 12 is determined by the spring force applied through a central piston member (not shown) onto the cam face. The body member 12 is pivotally mounted related to the base 14 by means of central pivot pin 18 which connects through central opening 19 at the base of the binding. As the skier begins to lose his upright stability, external forces act through his boot and toe cleat onto the body member 12. If the external forces are above the threshold level, the body member 12 undergoes rotation about pivot pin 18. The spring force is usually under the confining and releasably changeable pressure of plug 21. After rotation of the member 12 has occurred, say, in a counterclockwise direction as viewed in FIG. 1, through an arcuate angle α (release angle), the ski boot is released from the toe cleat 13.

As indicated in FIG. 1, the toe cleat 13 is not rigidly attached to the body member 12 but is free to pivot about a pivot pin 23 at the forward end of the body member. As shown, the toe cleat 13 is pivotally attached between the forward extending bosses 24 and 25. Since the axes of the pivot pins 18 and 23 are seen to be substantially parallel to each other but perpendicular to the broad surface of the ski runner 11, it is apparent that as the member 12 is exposed to the external forces to release the boot, rotation of the cleat is in a direction opposite to that of the member 12. As set forth in my U.S. Pat. No. 3,029,085, supra, such operation assures that the boot will not be wedged between the cleat 13 and the rearward forcing means. However, such anti-wedging action can only occur if, between the toe of the boot and the toe cleat, there is maintained a relatively rigid, surface engagement. In accordance with the present invention, engagement in the aforementioned style and construction is provided and maintained by means of an anti-early release linkage 30.

Anti-early release linkage 30 is connected between the stationary base 14 and the toe cleat 13 to keep centerlines of the toe cleat and the boot aligned during operation of the ski binding 10. In FIG. 1, the linkage 30 comprises a series of gears, including stationary spur gear 31 in fixed contact with hub 16 of the base 14 solid to the ski runner 11, and a pair of pinion gears 32 and 33 mounted to a common shaft 34 rotatably attached between bosses 24 and 25 of member 12. Gear 32 is seen to be in tangential contact with stationary gear 31; gear 33 in turn is seen to be in tangential contact with sector gear 35 formed at the hub of the cleat 13. Sector gear 35 is con-

structed so that the number of gear teeth on each side of centerline D—D defines a sector angle θ which is greater than the release angle α of the binding. Since the toe cleat 13 is meshed through the pinion gears 32 and 33 to the stationary spur gear 31, until the binding undergoes rotation, the toe cleat 13 is solid to the ski runner 11. However, as the binding is forced into rotation (external forces act through the boot and cleat onto the central rotating body member 12), the common shaft 34 is caused to rotate. Pinion gear 32 is seen to be in meshing contact with stationary spur gear 31 while in turn the other pinion gear 33 is rotatively attached to sector gear 35 integrally formed at the hub of toe cleat 13.

Absent initiating movement of the body member 12, however, the toe sole of the boot is solidly retained within the cleat 13 even though the forces acting therebetween are quite large and the sole-cleat combination is without the use of grooves, notches, or the like. Extent and duration of the rotation of the cleat 13 is directly linked, say, 1:1, to the angular rotation of the rotating body member 12 but is in opposite angular direction. The ratio of the linkage can be changed, if desired, from the preferred ratio to values above or below the norm.

It should also be noted that in acting to prevent early release of the boot from the cleat, as discussed above, the linkage 30 does not prevent, or in any way interfere, with the automatic return of the body member 13 from the extremity of its side-ward excursion after the external forces acting on the binding terminate. Further, as the member 12 approaches its neutral point, after such excursions, the linkage 30 further aids in rapidly dissipating any momentum which could cause the body member 12 to overshoot the neutral position. This is achieved by designing the linkage 30 as that its internal meshing force is greater than the momentum derived by the body member 12 during return to the neutral position from an arcuate extremity.

With regard to the above-described features, it should be apparent that the anti-early release linkage 30 of the present invention has special advantage in conjunction with the ski binding described in my U.S. Pat. No. 3,430,971, issued Mar. 14, 1969, supra. In that patent, the rotation body member 12 always generates a net return force acting on the rotating member 12 to return that member to its neutral position after external forces acting on the binding are terminated.

FIG. 2 illustrates the second embodiment of the anti-early release linkage of the present invention. In FIG. 2, the anti-early release linkage is generally indicated at 50 and is seen to be movably positioned between the toe cleat 41 and the base member 42, the toe cleat 41 being pivotally mounted by pin 43 to the rotating member 44. The base member 42 and the rotating member 44 are as previously described, the member 44 being pivotally mounted by pin 45 to the base member 42 solid to the ski runner 46.

As shown in FIG. 2, the linkage 40 includes a central yoke 47 fixedly positioned about hub 48 of the base 42 solid to the runner 46, and a pair of lever members (bars) 49 and 50 pivotally attached at one end, to the yoke 47 and, at the other end, to toe cleat support 51. Toe cleat support 51 is seen to include webleike base member 52 parallel to the broad space of the ski runner 46 terminated in an arcuate upright abutment 53. The base member 52 also includes a pair of central openings 54 for receiving tabs 55 attached to the bottom surface of toe cleat 51.

However, levers 49 and 50 are not fixed rigidly at their contact pins p_1 , p_2 and p_3 , p_4 on the yoke 47 and toe cleat support 51, respectively. Instead, they are permitted to pivot in a common plane through the pins p_1 , p_2 and p_3 , p_4 . The aforementioned common pivoting plane shall also seem to be substantially normal to pivot pins 43 and 45. The length of the levers 49, 50 (as measured between pins p_1 , p_3 and p_2 , p_4) are identical, and the spacing—in a lateral direction—between the pins p_1 , p_2 , and p_3 , p_4 is also preferably the same. In this application, the term "lateral" refers to a direction substantially normal to centerline E—E of the runner 46. As indicated, pins p_1 , p_2 are laterally spaced a distance equal to that separating pins p_3 , p_4 .

Since the pivot pin 43 of the toe cleat 41 is not coincidentally positioned with respect to pins p_3, p_4 on cleat support 51, it is apparent that the cleat 41 is not permitted to move in rotation without concomitant rotation of member 44. But when member 44 undergoes rotation, in the manner previously described, cleat 41 and toe cleat support 51 are carried in rotation therewith. Since the levers 49, 50 are pinned at one end to cleat support 51 (at pins p_3, p_4), and, at the other end, to yoke 47 (at pins p_1, p_2), it is apparent that pins p_3, p_4 will trace separate and distinct arcuate paths 56, 57 during operation, the radii of such paths being equal to the lengths of the levers 49 and 50 centered at pins p_1, p_2 , respectively. During rotation, the direction of movement of the pins p_3, p_4 along paths 56, 57 is seen to be the same. Relative to pivot point pin 43 of the cleat support member 51, the incremental absolute cord distances at instantaneous positions of the pins remain constant as the release angle of the binding is approached. By careful control in the design of the length of the levers 49, 50, as well as in the distance separating the pins p_1, p_2 , and p_3, p_4 , however, the ratio of the linkage between the cleat 41 and the rotating member 44 can be changed from the preferred value, say 1:1, to values below or above the norm.

Engagement of the skier's boot with toe cleat 41 is also facilitated by the relative positioning of the concave surfaces 58 and 59 of the toe cleat 41 and cleat support 51, respectively, relative to one another. As shown, the tabs 55 of the cleat 41 can be positioned within openings 54 of the cleat support 51 so that the surfaces 58 and 59 are positioned offset, vertically, with respect to each other. The sole of the toe of the boot, when placed in engagement with the concave surfaces 58 and 59 is prevented from lateral, as well as vertical displacement. In that way, when the release angle, position, of the binding is actually attained, the toe cleat 41 and body 44 can be made to yieldably remain, locked at the extremity of the sidewise excursion.

Accommodation of the boot soles of different thicknesses is facilitated by the toe cleat 13 and 41 of FIGS. 1 and 2, respectively, in two ways:

1. In FIG. 1, the entire toe cleat 13 is vertically adjustable. The pin 23 is in the form of a screw, threadably engaged into hub 35 of the cleat 13. The openings in the bosses 24 and 25 are slightly larger than the outside diameter of the screw rotation. The lower end of the pin 23 is enlarged, after assembly, and bears against the underside of boss 25 to prevent vertical movement upwardly of the pin 23. Rotation of the pin 23 will thus cause the cleat 13 to rise or descent, depending upon the direction of rotation. During upward or downward movement of the cleat, it should be noted that the mating teeth of the pinion gear 33 always meet with the teeth of section gear 35 since the total width of pinion gear 33 is wider than the incremental, vertical distance the cleat 13 may travel.

2. In FIG. 2, only the toe cleat 41 is vertically adjustable. The toe cleat 51 remains fixed in elevation. Adjustment of the toe cleat 41 is accomplished in the following manner similar to that previously described. The pin 43 is threadably engaged to the cleat 41 so that rotation of the pin 43 will cause the cleat 41 to rise or descend. The tabs 55 are of sufficient length to be retained within the opening 54 of the cleat support 51 irrespective of the total incremental movement of the cleat 41. Thus, the tab 55 must be at least equal to the total incremental vertical travel distance permitted the cleat 41.

The toe cleat described with reference to either FIG. 1 or FIG. 2 is formed to present concave surfaces which match the shape of the toe of the skier's boot. It is evident, however, that in some applications, say where the toe cleat is released from the boot by rotation in a vertical plane through the ski runner, reshaping of the toe cleat may be necessary.

From the foregoing description of embodiments of the present invention, it should be evident that modifications can occur without departure from the intended scope of the invention. For example, while the present invention has been illustrated in FIGS. 1 and 2 in association with a toe cleat which rotates in a horizontal plane relative to the ski runner, it is

evident that the invention can also be used with known ski bindings in which the toe cleat releases the ski boot by rotation of the cleat in a vertical plane through the runner. Likewise, from the foregoing description, the invention also evidently comprehends associative use with known ski bindings having yieldable means such as spring means positioned on the central body member in cooperative contact with the toe cleat instead of in contact with the stationary base 14 and 42 of FIGS. 1 and 2 respectively. Accordingly, the invention should be given the broadest interpretation in light of the following claims.

What is claimed is:

1. In combination with a ski binding adapted to be pivotally mounted on a ski runner for yieldably holding a ski boot relative thereto, including
  - a. a central body member adapted for pivotal mounting on said ski runner for rotation from a neutral position through a preselected release position in a rotational plane substantially parallel to said ski runner,
  - b. stationary base means pivotally mounted to said central body means to effect release of said boot from said binding at said preselected release position, said stationary base means adapted to be mounted solid to said ski runner yet to be pivotally mounted to said central body member,
  - c. a cleat member including mounting means for pivotally mounting said cleat member to said central body member,
  - d. yieldable means cooperative with one of said cleat member and stationary means for yieldably holding said body member in at least said neutral position yet allowing rotation of said body member in said rotational plane through said release position to effect release of said boot from said binding, the improvement comprising
    - i. anti-early release linkage means interconnected between said stationary base means and said cleat member,
    - ii. said linkage means including yieldable cooperative means connected to and movable with said central body member so that when said central member is placed in rotation, said cooperative means causes counter rotation of said cleat member in an opposite angular direction with said rotation of said central member.
2. The improvement of claim 1 in which said stationary base means includes cooperative support means connected to said yieldable cooperative means to prevent rotation of said cleat member relative to said central body member absent rotation of said central body member relative to said stationary base means.
3. The improvement of claim 2 in which the yieldable cooperative means includes rotatable gear means threadably connected to said cleat member and in which said cooperative support means includes a stationary gear means connected solid to said stationary base means and threadably connected to said gear means.
4. The improvement of claim 2 in which said yieldable cooperative means includes lever means, first pin means for pivotally connecting said lever means at one end, to a cleat support means on said cleat member; and said cooperative support means includes second pin means at the other end of said lever means, for pivotally connecting said lever means to said stationary base means.
5. The improvement of claim 2 in which said mounting means for said cleat means is a pin carried on said cleat member in parallel relationship to the axis of rotation of said body member relative to said stationary base means and, cooperative means connected to said pin for raising and lowering the cleat member relative to said stationary base means, and in which said anti-early release linkage is made to allow for said raising and lowering of said cleat member.
6. The improvement of claim 3 in which said yieldable means includes means for automatically returning said cleat

member from any sidewise excursion uninhibited by the operation of said yieldable cooperative means and said cooperative support means of said anti-early release linkage.

7. The improvement of claim 1 in which

d. yieldable means is further characterized by cooperative contact between said cleat member and said central body member for yieldably holding said body member in at least said neutral position, yet allowing rotation of said body member in said rotational plane through said release

5

10

position to effect release of said boot from said binding.

8. The improvement of claim 1 in which said

d. yieldable means is further characterized by cooperative contact between said stationary means and said central body member for yieldably holding said body member in said rotational plane through said release position to effect release of said boot from said binding.
